ADJUSTABLE RAILROAD JOURNAL LINER

Walter J. Walstad, Flint, Mich.

Application November 3, 1954, Serial No. 466,599

1 Claim. (Cl. 308—54)

This invention relates to railway car journal box liners and brasses wherein the contacting elements are positioned in the upper end of a journal box and wherein, due to wear, the diameter of the journal or axle is continuously reduced; and in particular, a journal box, brass or liner having hinged wearing plates held by spaced set screws wherein the positions of the wearing plates are adapted to be adjusted to compensate for the gradually reducing diameter of the journal.

The purpose of this invention is to provide means for continuously adjusting the inner surface of the brass of a railway car journal box so that the same bearing elements may be used throughout the life of the journal.

With ordinary use, a conventional journal or axle of a railway car decreases from the original size, such as 5½" in diameter to a minimum size, such as 5", and is then discarded. As an example, in being reduced from a 5½" journal to a 5" journal, open spaces are found on the sides and the only actual bearing surface is at the top. With this thought in mind, this invention contemplates the use of hinged bearing segments in the liners with set screws positioned to be adjusted to hold outer edges of the bearing segments in contact with the journal continuously throughout the different range of sizes.

The object of this invention is, therefore, to provide means in a railway car journal box liner whereby wearing surfaces of the liner are adapted to be adjusted to journals or axles of different diameters.

Another object of the invention is to provide adjusting means in a journal box liner without increasing the size of the liner and wherein the parts are adapted to be installed in journal boxes now in use.

A further object of the invention is to provide an improved railway car journal box liner in which the bearing surface thereof is adjustable and in which the device is of a simple and economical construction.

With these and other objects and advantages in view, the invention embodies an improved railway car journal box liner patterned to be installed in the upper end of the journal box and having wearing elements hinged at the center and adapted to be adjusted with set screws threaded in the sides of the liner.

The invention also includes a reinforcing center strip corresponding to the end plates of a railway car journal box whereby the cover or wall of the journal box is supported at the ends and center.

Other features and advantages of the invention will appear from the following description, taken in connection with the drawing, wherein:

Figure 1 is a cross section through a railway car journal box with the box and axle shown in broken lines and showing in particular a liner with hinged wearing elements therein, said section being taken on line 1—1 of Figure 2.

Figure 2 is a view looking upwardly toward the under surface of the bearing showing the hinge pins or screws extended inwardly from the ends of the liner and showing the positions of the set screws for adjusting the positions of the wearing elements.

2

Figure 3 is a cross section through the bearing taken on line 3—3 of Figure 2, the wearing elements being adjusted to positions for contacting a journal of a reduced diameter.

5 Figure 4 is a view showing the hinged wearing elements with the liner and other parts omitted.

Referring now to the drawing, wherein like reference characters denote corresponding parts, the improved bearing of this invention includes wearing segments 10 and 11, screws 12 and 13 pivotally connecting the segments, a continuous liner 14 having end plates 15 and 16 and a center rib 17 and set screws 18 threaded in openings 19 in the liner or brass and positioned to engage outer surfaces of the segments 10 and 11 whereby the segments are adjustable to compensate for wear of journals or axles, as indicated by the numeral 20.

The liner or brass 14 is patterned to be installed in the upper portion of an opening 21 in a journal box or bearing, as indicated by the numeral 22 and as shown in broken lines, and with the liner positioned as shown in Figure 1, the segments 10 and 11 are adapted to engage the surface of a journal or axle. As the journal or axle wears, such as from the large diameter indicated by the broken lines 20 to the smaller diameter as indicated by the broken lines 23, the positions of the segments are adjusted accordingly by the set screws 18.

In the design shown, the brass or liner 14 is formed with a flat upper surface 24 and inclined surfaces 25 and 26 at the corners, however, it will be understood that the brass or liner may be designed to correspond with upper inner surfaces of journal boxes or other types and designs. The edges of the liner are provided with vertically disposed walls 27 and 28 and projections 29 and 30 are provided at the lower edges of the walls. The flanges 15 and 16 are provided at the ends and a similar flange, as indicated by the numeral 17 is provided at the center, and as shown in Figure 3, the flange 17 forms a rib on the inner surface of a cavity 31 in which the segments 10 and 11 are positioned to prevent lateral displacement of the segments 10 and 11.

The segment 10 is provided with tongues 32 and 33 that extend into recesses 34 and 35, respectively, in the segment 11 and the segment 11 is provided with meshing tongues, as indicated by the numerals 36 and 37 and which extend into recesses 38 and 39, respectively, of the segment 10.

The edges of the liner 14 are provided with stepped shoulders 40 and 41 on one side and 42 and 43 on the other which correspond with recesses in the journal box.

50 The screw 12 extends through an opening 44 in the end wall or flange 15 and also through an opening 45 in the tongue 32 of the segment 10 providing a pivot pin for pivotally connecting the segments at one end. The extended end of the pin is threaded into an opening 46 in the tongue 36 and the extended end of the pin 13 at the opposite end of the bearing is threaded into an opening 47 in the tongue 33. The pin 13 extends through an opening 48 in the tongue 37 and also through an opening 49 in the flange or end wall 16.

60 Should it be desired to carry the rib or center flange 17 downwardly to the surface of the axle or journal to correspond with the end walls 15 and 16, segment assemblies, as shown in Figure 4, may be provided at both sides of the rib.

65 With the parts assembled as illustrated and described, the improved adjustable journal bearing is installed above the journal or axle in the upper end of the journal box and when used with a new bearing the set screws 18 are withdrawn to the positions shown in Figure 1, whereas, in installing the device in an old journal box where the diameter of the journal or axle is reduced the set screws 18 are set so that the end surfaces of the segments 10

3

and 11 contact the surface of the journal. These wearing plates or segments are adapted to be adjusted as the journal wears so that continuous contact is provided between the inner surfaces of the bearing elements and the journal.

The wearing elements or segments 10 and 11 are adapted to be removed and replaced as desired.

It will be understood that modifications, within the scope of the appended claim, may be made in the design and arrangement of the parts without departing from 10 the spirit of the invention.

What is claimed is:

In a bearing for use with a car journal bearing in a railway car journal box, the combination which comprises a brass having a cavity in the under surface with 15 flanges at the ends of the cavity and with a rib corre-

4

sponding with the flanges in the center of the cavity, hingedly connected wearing segments pivotally mounted in the brass and positioned with the pivotal mounting in a vertical plane extended through the axis of a journal 5 of the journal box, and set screws threaded in the brass and positioned to engage the upper surfaces of extended ends of the segments.
